UNITED STATES PATENT OFFICE.

FRED C. TISCHHAUSER, OF EDWARDSVILLE, ILLINOIS.

PACKAGE TIE.

Application filed April 17, 1922. Serial No. 553,665.

To all whom it may concern:

Be it known that I, FRED C. TISCHHAUSER, a citizen of the United States, residing at Edwardsville, in the county of Madison and 5 State of Illinois, have invented certain new and useful Improvements in Package Ties, of which the following is a specification.

This invention relates to new and useful improvements in package ties, and has for 10 its principal object to provide a simple and economical device of this character which may be made from a single piece of metal and is highly practical and efficient in use.

With the foregoing and other objects in 15 view that will appear as the nature of my invention is better understood, the same consists in the novel features of construction illustrated in the drawings and more particularly pointed out in the appended claims.

20 In the accompanying drawings, which are for illustrative purposes only and are therefore not drawn to scale:—

Figure 1 is a plan view, illustrating the application of my invention.

25 Fig. 2 is a vertical transverse section, taken on line 2—2 of Figure 1 and Figure 3 is a vertical section taken through one of the tie hooks.

Referring to the drawings for a more particular description of my invention and in 30 which drawing like parts are designated by like reference characters throughout the several views, A designates a package, B the binding cord and C my improved package 35 tie.

As shown, my package tie is cast or stamped in a single flat piece of metal and comprises the circular body portion 1, the outwardly projecting diagonally disposed 40 ears 2 and 3, respectively, the outwardly projecting lug 4 adjacent to and contiguous with the ear 2 and the handle 5 which is disposed at an angle of approximately 45° with the transverse axis of the binder and 45 extends in a direction opposite to that of the ears 2 and 3. The outer end of the handle 5 is provided with an enlarged perforated head 6 for convenience in holding.

The outer end of lug 4 is provided with a 50 transverse opening 7 to receive one end of the binding cord 8 and the ears 2 and 3 with upwardly bent longitudinally disposed hooks 9 which are formed by struck up portions of the metal blank from which the binder is 55 made. The body portion 1 of the binder is also formed with the semi-disc shaped clips

10 formed by slitting the metal blanks at a and b and bending the outer edges and ends 11 and 12, respectively, of the clips upwardly and inwardly on a gradual curve. 60

In practice, the package tie C is laid flatwise on the package to be tied and the binding cord 8 first passed lengthwise around the package, then around and under the clips 10, and then transversely around the package 65 with its free end extending diagonally under the hooks 9. By means of my invention, a package may be quickly and securely tied while the binding cord cannot slip or become loose. 70

From the foregoing description taken in connection with the drawings it is thought that the construction, advantages and novel features of my invention will be readily understood without requiring a more extended 75 explanation.

Having described my invention, what I claim as new and desire to secure by Letters Patent, is:—

1. A package tie formed in a single piece 80 of metal and comprising a pair of centrally and oppositely disposed semi-disc shaped clips whose outer edges and ends are bent upwardly and inwardly on a gradual curve and under which the binding cord is passed during the tying operation, a handle extending at angle from the body of the package tie, a pair of diagonally disposed ears extending outwardly from the body portion in a direction opposite to that of the handle and 85 upwardly bent hooks formed on said ears and under which the binding cord is passed. 90

2. A package tie formed in a single piece of metal and comprising a pair of centrally and oppositely disposed semi-disc shaped 95 clips whose outer edges and ends are bent upwardly and inwardly on a gradual curve and under which the binding cord is passed during the tying operating, a handle extending at an angle from the body of the 100 package tie, a pair of diagonally disposed ears extending outwardly from the body portion in a direction opposite to that of the handle, upwardly bent hooks formed on said ears and under which the binding cord is 105 passed and a lug extending transversely from said body portion and formed with a transverse opening to receive one end of the binding cord.

In testimony whereof I affix my signature. 110

FRED C. TISCHHAUSER.
